UNITED STATES PATENT OFFICE.

LOGAN R. WHITNEY, OF LOUISVILLE, KENTUCKY, ASSIGNOR TO WHITNEY-JARVIS COMPANY, OF LOUISVILLE, KENTUCKY, A CORPORATION OF KENTUCKY.

CAN OPENER.

Application filed May 8, 1926. Serial No. 107,713.

This invention relates to an improved device to be used in combination with a can opener for the purpose of forming an opening in a can to receive the cutting blade 5 of a can opener.

The primary object of this invention is to produce a device which can readily and easily be used in conjunction with a can opener.

10 The chief novelty lies in the simplicity of operation.

Other novelty lies in the means whereby two distinct operations which would ordinarily require two tools is performed with 15 a single tool.

Further novelty will be shown in the drawings and specification.

Referring to the drawing:

Figure 1 is a perspective view of a cylindrical metal can with the can opener in position for making the initial cut in the can and the dotted lines show the position of the opener after the initial cut has been made.

Figure 2 is a perspective view of a cylindrical metal can with the opener in position ready to cut the top of can off. Dotted lines show the position of opener after the first cut with the knife edge has been made.

Figure 3 is a fragmentary detail illustrating the portion of the puncturing blade and guard.

Referring to the details of the drawings, numeral 1 designates a cylindrical container, having a top 2, forming a lip 3. In conjunction with the cylindrical container is a can opener 4, having a head 5, with a flange 6 at right angles to a cutter blade 8. At one end of cutter blade 8 is a cutter point 7. At the other end the cutter blade drops 40 down forming a shoulder 9 to knife edge 10. Directly beneath the knife edge 10 is a projection 11 parallel to knife edge 10 which acts as a fulcrum against the container when the knife edge is in operation.

45 As actually used, the flange 6 will be placed over lip 3 so that cutter point 7 will come in contact with the side of cylindrical container 1. The handle of can opener 4 will then be revolved in a counter clock-

wise direction to assume the dotted position 50 shown in Figure 1. This operation forces the cutter point 7 into the container and as this movement is continued cutter blade 8 will be forced against the side of container 1, thus making an opening the length of cutter blade 8. The cutter point 7 is then removed and the knife edge 10 inserted in the opening as shown in Figure 2. Projection 55 11 resting against the side of the cylindrical container acts as a fulcrum when the handle of can opener 4 is operating in a clockwise direction to take the position of dotted line indicated in Fig. 2.

This causes the knife edge 10 to swing outwardly in a clockwise direction with a 60 shearing cut. The opener is then moved into a new position, this new position being at the end of the cut just made and the opener assumes the position as shown in solid lines in Figure 2. The cutting stroke is 65 repeated until the side of the container has been completely cut.

Having described my invention what I claim is:

1. A can opener comprising a plate of 70 material shaped to form a handle, a puncturing blade extending laterally therefrom, a guard bent at right angles to said plate, and having an edge spaced from said blade to position the latter at a predetermined distance from the top of a can, said guard also having a fulcrum point adapted to engage the inside edge of the rim of a can with the said puncturing blade positioned at said predetermined distance below the top of and 75 outside of said can.

2. A can opener set forth in claim 1 having a cutting blade extending across the end of said plate, a gauge member stamped from said plate at right angles thereto and on the side opposite to the said guard, said gauge member having a gauging edge spaced at the same distance from said cutting blade as the gauging edge on said guard member is spaced from said puncturing blade. 80 85 90 95

In testimony whereof I affix my signature.

LOGAN R. WHITNEY.
